DESIGN FOR A DRESS

Norman Pohl, Cedarhurst, N. Y.

Application January 15, 1938, Serial No. 74,329

Term of patent 3½ years

To all whom it may concern:

Be it known that I, Norman Pohl, a citizen of the United States, residing at 530 Park Place, in the county of Nassau, city of Cedarhurst, Long Island, State of New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

The characteristic feature of my design resides in the specific, angular, double collar and the piping trimmed angular pockets in combination, on the specific dress as shown.

I claim:

The ornamental design for a dress substantially as shown and described.

NORMAN POHL.
